[57] CLAIM

The ornamental design for a sleigh bed, as shown and described.

DESCRIPTION

FIG. 1 is a front perspective view of a sleigh bed embodying my new design;

FIG. 2 is a side elevational view of my new design, the opposite side which is a mirror image thereof;

FIG. 3 is a front elevational view of my new design;

FIG. 4 is a front elevational view of the headboard of the design, shown for convenience of illustration;

FIG. 5 is a front elevational view of the footboard of the design, shown for convenience of illustration;

FIG. 6 is a top plan view of the design;

FIG. 7 is a cross-sectional view of the design taken along line 7—7 of FIG. 3;

FIG. 8 is a partial cross-sectional view taken along line 8—8 of FIG. 4; and,

FIG. 9 is a partial cross-sectional view taken along line 9—9 of FIG. 5.
